UNITED STATES PATENT OFFICE.

JAMES S. INGALLS, OF MINNEAPOLIS, MINNESOTA.

DESIGN FOR A HEADLIGHT LENS.

•60,751.

Specification for Design.

Patented Apr. 4, 1922.

Application filed July 22, 1921. Serial No. 486,893. Term of patent 3½ years.

To all whom it may concern:

Be it known that I, JAMES S. INGALLS, a citizen of the United States, residing at Minneapolis, in the county of Hennepin and State of Minnesota, have invented a new, original, and ornamental Design for a Headlight Lens, of which the following is a specification, reference being had to the

accompanying drawing, forming part thereof.

The figure is an elevation of a headlight lens showing my new design.

I claim:

The ornamental design for a headlight lens as shown.

JAMES S. INGALLS.
